UNITED STATES PATENT OFFICE.

HARRY HOLBROOK, OF SHAWNEE ON DELAWARE, PENNSYLVANIA, ASSIGNOR TO WORTHINGTON MOWER COMPANY, OF SHAWNEE-ON-DELAWARE, PENNSYLVANIA, A CORPORATION OF DELAWARE.

GAME.

Application filed December 1, 1922. Serial No. 604,150.

To all whom it may concern:

Be it known that I, HARRY HOLBROOK, United States citizen, residing in Shawnee on Delaware, Pennsylvania, have invented the following described Improvements in Games.

The invention relates to the game of golf and consists in a set of devices placed in the field of play and designed to serve as datum points wherewith to locate the position of a ball falling in the rough or long grass adjoining the fairway. It is a matter of common experience with golf players that it is difficult to mark the spot in the rough 10 where a ball lands, so as to be able to find it promptly. This is ordinarily due, as I have ascertained, to the absence in the background and surrounding landscape of any distinctive objects which the eye, while intently fixed on the moving ball, can recognize and use as the basis of ascertaining its 20 location. This invention provides such objects, herein termed target devices, the same being adapted to be placed in positions suitable for the purpose, as more fully explained below. The use of these targets is found to give a very substantial assistance in locating balls which fall in the rough and, besides saving time and reducing expense for lost balls, also promotes the enjoyment of the game in general.

The accompanying drawings show in Figure 1 a plan of one link of a golf course, supplied with this invention, and Figures 2, 3, 4 and 5 represent examples of suitable targets in their preferred form of construction. In Figure 1, the reference numeral 1 represents the driving tee; 2 the short grass or fairway; 3, the putting green; 4 traps or bunkers; and 5 the adjoining long grass or rough. According to the extent of its area, each section or portion of the rough is equipped with one or more of the target devices which are set up in appropriately distributed positions, so as to be plainly visible from the tee, or other point where the shot is made, and preferably they are located in the rough itself or where off-direction balls commonly fall. A suitable set of

locations is indicated in Figure 1, where the targets are marked 6. The several targets are shaped, marked or painted so as to be conspicuous and sufficiently prominent to enable them to be seen and recognized by the indirect vision of the eye, that is to say, to enable one or more of them to be recognized when the eye is focussed elsewhere, as on the ball or on the spot where it was seen to land or stop and each target in a group is made distinctively different from the others in the group, so that there will be little likelihood of confusing one with another.

With the rough thus equipped, the flight of the ball is followed by the eye and, as it nears the ground, the eye is able to pick up one or more of the neighboring targets and can thereby recognize the position of the ball with reference to it or to them, so that when the ball has come to rest its position is thereby identified. As shown in Figures 2 to 5, each target may be constituted of two parallel post members 7, united at one end by a rectangular plate 8, the other ends being pointed, so that they may be easily pushed into the ground. The plates are painted white, with a distinctive design on each, which may be in red, or other color calculated to attract attention. In the form at present preferred they are about 42 inches long by 6 inches wide. Obviously the detail construction of the target is subject to wide variation, according to the preference of the maker and the means whereby they are mounted in the rough may obviously also be varied. They could, for example, be supported by feet or a pedestal or in any other way which would enable them to be moved by the player, if one of them should constitute an obstruction to his ball or the swing of his club.

Having described my invention and the best mode in which I now contemplate employing the same, what I claim as the subject of this patent is:

1. In the game of golf, the combination with the fairway and the adjoining rough, of a set of targets of conspicuous and singu-

lar appearance placed in said rough and serving as datum points wherewith to fix the location of the ball.

2. In the combination of claim 1, a set of target devices similarly shaped and each bearing a conspicuous distinctively different marking.

3. In the combination of claim 1, a set of targets having means for removably supporting them in the rough. ¹⁰

In testimony whereof, I have signed this specification.

HARRY HOLBROOK.
